(57) **CLAIM**

The ornamental design for a frame for cycle as shown and described.

DESCRIPTION

FIG. 1 is a top, front and right side perspective view of a frame for cycle showing our new design;

FIG. 2 is a bottom, rear and left side perspective view thereof;

FIG. 3 is a top, rear and right side perspective view thereof;

FIG. 4 is a front elevational view thereof;

FIG. 5 is a rear elevational view thereof;

FIG. 6 is a left side view thereof;

FIG. 7 is a right side view thereof;

FIG. 8 is a top plan view thereof;

FIG. 9 is a bottom plan view thereof; and,

FIG. 10 is an enlarged view of portion 10 in FIG. 1.

The evenly dashed broken lines in the drawings illustrate portions of the frame for cycle which form no part of the claimed design.

The dot-dashed broken lines illustrate the boundary of the enlarged view and form no part of the claimed design.
